AEROMUFFLER

Marvin E. Rutherford, Abilene, Tex., assignor of
one-third to Anthony M. De Muth, Houston,
Tex., and one-tenth to Carroll W. Rogers, Ab-
ilene, Tex.

Application November 2, 1938, Serial No. 238,471

8 Claims. (Cl. 181—64)

This invention relates to internal combustion engines, and more particularly to an improved muffler for use with an engine of this type.

An object of this invention is to provide an improved muffler for an internal combustion engine which is so constructed as to eliminate the back pressure normally caused by conventional mufflers.

Another object of this invention is to provide a muffler of this kind which includes a pair of rotary elements actuated by the flow of gases therethrough which act to form a substantial vacuum in order to relieve the back pressure on the exhaust side of the engine, thereby facilitating the removal of the exhaust gases and substantially increasing the power of the engine.

A further object of this invention is to provide a muffler which is adapted to eliminate the noise of the exhaust due to the sudden expansion of the exhaust gases in the atmosphere.

Embodying the foregoing aims essentially and to others which may hereinafter appear, the invention consists of the novel construction, combination and arrangement of parts as will be more specifically referred to and illustrated in the accompanying drawings, wherein are shown embodiments of the invention, but it is to be understood that changes, variations and modifications may be resorted to which fall within the scope 30 of the invention as claimed.

In the drawings:

Figure 1 is a detail side elevation of a muffler constructed according to an embodiment of this invention,

Figure 2 is a longitudinal section taken on the line 2—2 of Figure 1,

Figure 3 is a detail end elevation of the device at the intake end thereof,

Figure 4 is a detail end elevation at the discharge end of the device,

Figure 5 is a sectional view taken on the line 5—5 of Figure 1,

Figure 6 is a sectional view taken on the line 6—6 of Figure 1,

Figure 7 is a fragmentary longitudinal section partly in detail of a modified form of this device, and

Figure 8 is a fragmentary sectional view partly in detail of a further modification of this device.

Referring to the drawings, the numeral 10 designates generally a cylindrical housing which at one end thereof is provided with an annular flange 13. The opposite end of the housing 10 is provided with a frusto-conical member 11 terminating in a flange 12 at the outer or smaller

end thereof. The flange 12 is adapted to abut against the inner wall 14 of a fan housing 15. The fan housing 15 is provided with an axially disposed intake opening 16 communicating with the outlet member 11. The fan housing 15 is provided with a disc shaped head or plate 17 having a centrally disposed cylindrical bushing 18.

A head 19 is secured as by bolts 20 to the flange 13, and this head 19 is provided with an intake 10 nipple 21 communicating with the housing 10. The nipple 21 is adapted to be connected to the exhaust side of an internal combustion engine so that the exhaust gases from the engine will discharge through the nipple 21 into the housing 15 10. The head 19 is provided with a centrally disposed cylindrical bushing 22, and the head 19 at the center thereof is provided with an opening 23 through which a shaft 24 extends. The shaft 24 extends axially through the housing 10, and 20 one end thereof engages in the bushing 22. The shaft 24 at one end thereof is reduced as at 25, and the inner race 26 of an anti-friction bearing engages the reduced shaft portion 25. The outer race 27 of the anti-friction bearing engages the 25 inner surface of the bushing or bearing member 22.

A packing 28 is disposed in the bushing 22 between the anti-friction bearing and the wall of the head 19, and a thrust plate 29 is interposed 30 between the outer end of the packing 28 and the bearing member comprising the races 26 and 27. A lubricating element 30 is secured to the bushing 22 and provides a means whereby a lubricating means in the form of oil or grease may be 35 forced into the bushing 22 for lubricating the bearing elements comprising the races 26 and 27 and the packing 28. A cap 31 is threaded onto the outer end of the bushing 22 so that the lubricating means may be retained in the bushing 40 and so that the shaft 24 may be released from the head 19. The shaft 24 may be released from the head 19 by removal of the cap 31 and removal of the anti-friction bearing from the reduced portion 25 of the shaft 24.

The opposite or outer end of the shaft 24 is provided with a reduced portion 32 about which an inner race member 33 engages. An outer race member 34 is disposed in the bushing 18, and anti-friction members such as balls 35 or the 50 like are interposed between the two race members 33 and 34. Balls 36 are interposed between the two race members 26 and 27. A packing 37 is disposed in the bushing 18 and a thrust plate 38 is interposed between the packing 37 and the 55

anti-friction bearing comprising the race members 33 and 34 and the balls 35. The head 17 of the fan housing 15 is provided with an opening 39 through which the shaft 24 extends. A lubricating fitting 40 is secured to the bushing 18 and provides a means for discharging a lubricating means interiorly of the bushing 18. The outer end of the bushing 18 is closed by means of a cap 41 which is threaded onto the bushing 18.

The shaft 24 has mounted thereon a plurality of blade members generally designated as 42 which are disposed in longitudinally spaced apart relation on the shaft 24 in the housing 10. These blade members 42 comprise impellers and are formed by securing blades 43 to a hub 44. The hub 44 engages the shaft 24 and is secured thereto as by a set screw 45 or like fastening means. A ring 46 is secured to the blades 43 and provides a reinforcing means to prevent bending of the blades 43. The impellers 42 are so positioned along the length of the shaft 24 that the force or movement of the exhaust gases will strike the impellers 42 and cause the shaft 24 to be rotated thereby. The exhaust gases will move longitudinally of the housing 10 entering the frustoconical member 11 and discharging through the opening 16 into the fan housing 15. The fan housing 15 is provided with a plurality of blades 49 which are secured to a hub 48 fixed as by a set screw 49 to the shaft 24.

When the exhaust gases enter the housing 15 they will effect rotation of the fan comprising the blades 47 and the hub 48. The fan housing 15 is provided with a discharge nipple 50 shown in greater detail in Figure 6, and this discharge member 50 is disposed on a tangent with respect to the fan comprising the blades 47 and the hub 48. The discharge member 50 may be connected to a suitable carry-off pipe or the like so that the exhaust gases may be carried to a suitable point for discharge into the atmosphere.

In Figure 7 there is disclosed a slightly modified form of this device wherein the impeller shaft 24a extends through an opening 51 provided in the cap 31a. The shaft 24a extends through the head 19a which is similar to the head 19, and a bushing 22a is carried by the head 19a. The shaft 24a is provided with a relatively long reduced portion 25a, and a pulley or grooved wheel 52 has the hub 53 thereof secured as by a key 54 or like fastening means to the shaft extension 25a. An anti-friction bearing comprising race members 26a, 27a, and balls 36 engage about the reduced portion 25a, and a packing 28a similar to the packing 28 is positioned in the bushing 22a. A thrust plate 29a is interposed between the packing 28a and the anti-friction bearing. The grooved pulley or wheel 52 is provided so that the shaft 24a may be positively rotated by means of a belt engageable with a driving pulley mounted on a shaft rotated by the engine proper.

With a construction of this kind the operation of the engine will effect rotation of the shaft 24a with the impellers mounted thereon so that a suction will be created in the muffler housing associated with the head 19a. It will, of course, be understood that if desired the driven member 52 may be in the form of a gear or sprocket depending upon the conditions existing with respect to a particular engine.

In Figure 8 there is disclosed a further driving means or modification wherein the shaft 24b is provided with a reduced extension 32b and the shaft 24b extends through a head or plate

17b having a bushing 18b. An anti-friction bearing comprising inner and outer race members 33b and 34b engage about the extension 32b and are positioned in the bushing 18b. Balls 35b are interposed between the two race members 33b and 34b. A packing member 37b is positioned in the bushing 18b and a thrust plate 38b is interposed between the outer end of the packing 37b and the anti-friction bearing.

A cap 41b having an axial opening 55 is threaded onto the bushing 18b, and the reduced shaft extension 32b extends through the opening 55. A propeller 56 is fixed as by a key 57 or other suitable fastening means to the shaft extension 32b, and this propeller 56 is adapted to be used where the muffler secured to the head 17b is used with an airplane engine where the force of movement of the air will provide the necessary power to drive the propeller 56.

In the use and operation of this device where the muffler 10 is connected to a motor vehicle, the exhaust side of the engine is connected to the intake nipple 21. The exhaust gases will enter the muffler 10 and upon striking the impellers 42 will effect rotation of the impellers 42. The exhaust gases will expand in the housing 10 and will move longitudinally through the housing 10 and be discharged through the opening 16 into the fan housing 15.

The movement of the gases in the fan housing 15 will cause rotation of the fan 15 in addition to the rotation of the fan 15 being effected by the rotation of the shaft 24 under the action of the impellers 42. The fan comprising the blades 47 will create a substantial suction through the housing 10 so that the exhaust gases will be prevented from forming a back pressure on the exhaust side of the internal combustion engine. In this manner the engine will run more smoothly than heretofore, and as the back pressure will be eliminated, an increased power will be effected and a reduction in the gas or fuel consumption will also be effected.

Where it is possible to provide a positive drive for the shaft 24, a driving member such as 52 may be secured thereto and connected to a suitable rotating part of the vehicle or engine. Where this is done, there will be a positive withdrawal of the exhaust gases and a substantial vacuum will be created on the exhaust side of the internal combustion engine which will assist in the withdrawal of the exhaust gases from the combustion chambers of the engine.

Where the muffler is attached to an airplane engine, the muffler may have the shaft 24b thereof positively rotated by an air driven propeller such as 56, and where this is done, a substantial vacuum will be created on the exhaust side of the engine. Where the device is used with an airplane engine, the muffler will substantially eliminate the noise of the exhaust gases so that where the airplane is used in warfare the engine cannot readily be detected by the noise of the exhaust gases as is the case with airplane engines at present in use.

This muffler may be constructed in the form of an attachment for a conventional internal combustion engine, and may be secured to the internal combustion engine without disturbing the present parts of the engine. The device can be constructed at a relatively small cost, and will last indefinitely.

What I claim is:

1. An exhaust muffler comprising a cylindrical housing having an intake at one end thereof, and

an outlet at the other end thereof, a shaft journalled axially of said housing, a plurality of impeller members fixed to said shaft, a fan housing communicating at the intake side thereof with said outlet, and a fan member in said fan housing and fixed to said shaft.

2. An exhaust muffler comprising a cylindrical housing having an intake at one end thereof, a cone-shaped outlet at the other end of said housing, a shaft journalled axially of said housing, a plurality of impeller members fixed to said shaft, a fan housing communicating at the intake side thereof with said outlet, and a fan member in said fan housing and fixed to said shaft.

3. An exhaust muffler comprising a cylindrical housing having an intake at one end thereof, a substantially frustro-conical member at the other end of said housing, a shaft journalled axially of said housing and said frustro-conical member, a plurality of impeller members fixed to said shaft in said housing, a fan housing communicating at the intake side thereof with the reduced end of said frustro-conical member, and a fan member in said fan housing fixed to said shaft.

4. An exhaust muffler comprising a cylindrical housing having an intake at one end thereof, a substantially frustro-conical member at the other end of said housing, a shaft journalled axially of said housing and said frustro-conical member, a plurality of impeller members fixed to said shaft in said housing, a fan housing communicating at the intake side thereof with the reduced end of said frustro-conical member, a fan member in said fan housing fixed to said shaft, and a drive member secured to said shaft exteriorly of said housing.

5. An exhaust muffler comprising a cylindrical housing having an intake at one end thereof and an outlet at the other end thereof, a shaft journalled axially of said housing, a plurality of impeller members fixed to said shaft in said housing, a fan housing communicating at the intake side thereof with said outlet, a fan member in said fan housing fixed to said shaft, said shaft at one end projecting exteriorly of said housing, and a grooved pulley fixed to said extended end of said

shaft and adapted to have an endless belt trained thereover for forcibly driving said shaft.

6. An exhaust muffler comprising a cylindrical housing having an intake at one end thereof and an outlet at the other end thereof, a shaft journalled axially of said housing, a plurality of impeller members fixed to said shaft, a fan housing communicating at the intake side thereof with said outlet, an extension integral with one end of said shaft and projecting exteriorly of said housing, and a propeller fixed to said extension.

7. An exhaust muffler comprising a cylindrical housing having an intake at one end thereof and an outlet at the other end thereof, a shaft disposed axially of said housing, a head at one end of said housing, a centrally disposed bushing carried by said head, one end of said shaft extending interiorly of said bushing, anti-friction bearing means engaging said one end of said shaft and said bushing to rotatably support said one end of said shaft in said head, packing means about said shaft between said anti-friction means and said head and disposed in said bushing, a fan housing communicating at the intake side thereof with said outlet, a fan member in said fan housing fixed to said shaft, a cylindrical bushing carried by said fan housing about said shaft, anti-friction bearing means in said second bushing engaging the opposite end of said shaft, and a second packing means in said second bushing.

8. An exhaust muffler comprising a cylindrical housing having an intake at one end thereof and an outlet at the other end thereof, a shaft in said housing, a plurality of propeller members fixed to said shaft, a fan housing communicating at the intake side thereof with said outlet, a fan member fixed to said shaft in said fan housing, a cylindrical bushing at one end of said first housing disposed about one end of said shaft, a second cylindrical bushing fixed to said fan housing and engaging about the opposite end of said shaft, anti-friction means in said first bushing, anti-friction means in said second bushing, and a cap threadably engaging said bushings.

MARVIN E. RUTHERFORD.
